(74) Attorney, Agent, or Firm—Kramer, Levin, Naftalis & Frankel LLP.

(57) **CLAIM**

The ornamental design for a portable lighting device, as shown and described.

DESCRIPTION

FIG. 1 is a front perspective view showing the new design, with the broken line showing for illustrative purposes only and forming no part of the claimed design;

FIG. 2 is an alternate front perspective view showing the new design, the only difference from FIG. 1 being that the device is shown in a retracted configuration;

FIG. 3 is a top plan view thereof, the bottom plan view, and right and left side elevation views being substantially similar;

FIG. 4 is a front elevation view thereof; and,

FIG. 5 is a rear elevation view thereof.
